UNITED STATES PATENT OFFICE.

WILLIAM O. ASHE, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE STRUCTURE.

Application filed March 30, 1927. Serial No. 179,495.

My invention relates to railway rolling stock and is particularly adapted for electric locomotives and consists in an improved radius bar and locomotive frame assembly.

5 In electric locomotives now in use a common arrangement is to have a radius bar fulcrum casting, for pivoting the trailer truck, detachably secured to the rear portion or cradle of the locomotive frame and 10 projecting forwardly thereof and beneath part of the electric motor mounted on the rear driving axle of the locomotive. When it is desired to remove the motor, it is necessary to completely disconnect the radius bar 15 fulcrum which is usually a heavy casting and difficult to handle.

The main object of my invention is to simplify the operation of removing the motor, and, briefly, I accomplish this object 20 by pivoting the fulcrum casting to the locomotive frame or cradle and swinging the fulcrum casting on its pivot out of its functioning position where it projects beneath the motor.

25 An additional object of my invention is to provide a cradle member and radius bar fulcrum member in which the forces in both members are resisted by abutting faces on the two members rather than by the bolts 30 or other elements which hold the two members in assembled position.

In the accompanying drawings which illustrate a selected embodiment of my invention,—

35 Figure 1 is a longitudinal vertical section through an electric locomotive cradle and the radius bar fulcrum assembled therewith, the rear driving wheel and its motor and the trailer truck being shown in dot-and-dash lines.

40 Figure 2 is a front elevation of the cradle with the motor supporting bar and the supported lugs on the motor being shown in dot-and-dash lines. This figure is drawn on a larger scale than Figure 1.

45 Figure 3 is a top view of the radius bar fulcrum casting also drawn on a larger scale than indicated in Figure 1.

The locomotive cradle is indicated at 1 50 and is shown as being formed of a one-piece casting which may be applied to the remainder of the locomotive frame but it will be understood that this element of my invention may constitute a part of the loco-

motive frame instead of being formed separately therefrom.

55 The front end of this casting is provided with bearings 2 for a drawbar and the front end of this casting is also provided with a shelf 3 on which rests the yoke 4, the ends 60 of which are depressed and support the motor lugs 5. The lower portion of the cradle is provided with depending ears 6 and between and to the rear of these ears is a depending lug 7 with a forwardly projecting flange 8. The radius bar fulcrum member 9 is supported at one end by a horizontal pivot pin 10 which extends through ears 6 and the forward end of the radius bar fulcrum casting is detachably secured to the 70 forward portion of the cradle by means of bolts 11.

75 The rear end of fulcrum member 9 is provided with a rearwardly projecting flange 12 adapted to engage flange 8 when the member 9 is in the horizontal position illustrated. The upper face of member 9 is provided with an upwardly extending flange 13 adapted to engage a thrust-receiving pad 14 provided on the forward end of cradle 1. 80 Flanges 12 and 8 serve to relieve pin 10 of the weight of the fulcrum casting and of the downward thrust of the rear end of the casting caused by upward thrust on the trailer truck pivot 15. Flange 13 and pad 85 14 serve to relieve the pin 10 and bolts 11 of any draft and buffing stresses. It will be understood that the holes for pin 10 and bolts 11 may be enlarged or slotted so that these flanges and the pad may function as 90 mentioned. Suitable pads 16 and 17 are provided on the opposing faces of the cradle and fulcrum casting adjacent bolts 11.

95 It will be understood that these interengaging surfaces on the cradle and radius bar fulcrum will be machined to more accurately fit each other.

When the locomotive is operating, the cradle and radius bar fulcrum casting will bear the ordinary relation to each other and 100 will be as strong as the ordinary construction in which these parts are bolted together. When it is desired to remove the motor, the locomotive is run over a pit, and the trailer truck disconnected and removed (the cradle 105 being supported upon a special truck); bolts 11 are then removed and the fulcrum casting 9 swung to the dot-and-dash position in-

dicated. The yoke 4 may then be unbolted from the motor lugs and from the cradle shelf 3 and moved forwardly and downwardly and the motor can then be lowered into the drop pit.

Obviously the details of my invention may be varied in a number of ways without departing from the spirit of my invention, and I contemplate the exclusive use of all such modifications of the structure illustrated and described as fall within the scope of my claims.

I claim:

1. In combination, a locomotive frame member, and a radius bar fulcrum member pivoted on said frame member to swing into and out of functioning position.
2. In a locomotive, a frame member, and a radius bar fulcrum member pivoted on said frame member to swing in a vertical plane to and from a functioning position.
3. In a locomotive, a frame member, a radius bar fulcrum member pivoted on said frame member to swing vertically, and a trailer truck radius bar pivotally connected to said fulcrum member to move about the same horizontally.
4. In a locomotive, a frame member, a radius bar fulcrum member pivoted at one end to said frame member so as to swing vertically, and a trailer truck pivoted to said fulcrum member at the other end thereof so as to swing horizontally.
5. In combination, a locomotive frame member, and a radius bar fulcrum member pivoted at one end on said frame to swing into and out of functioning position and extending horizontally from its pivotal connection with said frame member and provided with a radius bar pivot at its opposite end.
6. In combination, a locomotive frame member, a radius bar fulcrum member pivoted on said frame member to swing into and out of functioning position, detachable means for holding said fulcrum member in assembly with said frame member, and interengaging elements on said members for resisting the forces in each member independently of said means.
7. In a locomotive, a cradle, a radius bar fulcrum member pivoted on said cradle behind the forward end of the latter and ex-

tending in front of said end, a bolt located between the pivot point and said end for holding said fulcrum member in assembled relation with said cradle, and a fulcrum bearing for a trailer truck on the forward end of said fulcrum member.

8. In a locomotive, a frame member, a radius bar fulcrum member pivoted to said frame member to swing vertically, and interengaging surfaces on said members adjacent to their pivotal connection for supporting the adjacent portion of said fulcrum member irrespective of said connection.

9. In a locomotive, a frame member, a radius bar fulcrum member pivoted to said frame member to swing vertically, and interengaging surfaces on said members adjacent to the forward end of said frame member for resisting buffing and pulling forces irrespective of the pivotal connection between said members.

10. In an electric locomotive, a driving motor, a frame member at one side of said motor and supporting the later, a radius bar fulcrum assembled with said member and normally extending under said motor, said fulcrum being movable away from under said motor without being detached from said member.

11. A locomotive cradle having an integral bearing for supporting a radius bar fulcrum pivot pin.

12. A locomotive cradle having an integral bearing for supporting a radius bar fulcrum pivot pin and a radius bar fulcrum supporting element adjacent to said bearing.

13. A locomotive cradle having an integral bearing for supporting a radius bar fulcrum pivot pin, and a radius bar fulcrum supporting element and a radius bar thrust pad in spaced relation with said bearing.

14. A locomotive radius bar fulcrum having a pivot pin bearing and a support engaging element adjacent to said bearing.

15. A locomotive truck radius bar fulcrum having a pivot bearing and having a support engaging element and a thrust pad engaging element in spaced relation to said bearing.

In testimony whereof I hereunto affix my signature this 26th day of March, 1927.

WILLIAM O. ASHE.
